DESIGN FOR AN ENLARGEMENT VISUALIZER

Walter D. Teague, New York, and D'Arcy A. Young, Jr., Rochester, N. Y., assignors to Eastman Kodak Company, Rochester, N. Y., a corporation of New York

Application February 26, 1936, Serial No. 61,372

Term of patent 3½ years

To all whom it may concern:

Be it known that we, Walter D. Teague and D'Arcy A. Young, Jr., citizens of the United States, residing at New York city, in the county of New York and State of New York, and at Rochester, in the county of Monroe and State of New York, respectively, have invented a new, original, and ornamental Design for an Enlargement Visualizer, of which the following is a specification, reference being had to the accompanying drawing forming a part thereof.

In the drawing:

Fig. 1 is a perspective view of an enlargement visualizer showing our new design.

Fig. 2 is a rear elevation of the enlargement visualizer shown in Fig. 1.

Fig. 3 is a side elevation of the enlargement visualizer shown in Fig. 1.

We claim:

The ornamental design for an enlargement visualizer as shown.

Signed at Rochester, New York, this 20th day of February, 1936.

WALTER D. TEAGUE.
